UNITED STATES PATENT OFFICE.

ARCHIBALD D. MCKELLAR, OF CHICAGO, ILLINOIS.

SIGN.

1,384,911.

Specification of Letters Patent. Patented July 19, 1921.

Application filed August 28, 1917. Serial No. 188,671.

To all whom it may concern:

Be it known that I, ARCHIBALD D. MCKELLAR, a citizen of the United States, and a resident of the city of Chicago, county of Cook, and State of Illinois, have invented certain new and useful Improvements in Signs, of which the following is a specification.

My invention relates to improvements in sign members, and has for its object the provision of an improved construction of this character by means of which a large variety of signs may be exhibited in small space and the character of such signs readily 15 changed at will.

The invention consists in the combinations and arrangements of parts hereinafter described and claimed.

The invention will be best understood by reference to the accompanying drawings forming a part of this specification, and in which,

Figure 1 is a vertical section of a sign embodying my invention,

Fig. 2, a section taken at right angles to Fig. 1,

Fig. 3, a detail view illustrating driving gearing employed in the sign,

Fig. 4, a face view of the sign,

Fig. 5, a vertical transverse section of the sign, said section being taken on line 5—5 of Fig. 6,

Fig. 6, a horizontal section of the sign,

Fig. 7, a side view of a hopper employed 35 in the construction,

Fig. 8, a rear view of said hopper,

Fig. 9, a detail view of one of a plurality of sign members employed in the construction,

Fig. 10, a horizontal section taken on line 10—10 of Fig. 7,

Fig. 11, a detail section taken through one side of the lower portion of the hopper,

Fig. 12, a detail section illustrating the 45 arrangement of one of two transferring disks employed in the construction,

Fig. 13, a bottom plan view of the hopper, and

Fig. 14, a detail view at right angles to 50 Fig. 12.

The preferred form of construction, as illustrated in the drawings, comprises a suitable case 17 having a glass covered sight opening 18 in the front face thereof and equipped with a vertical elevator conveyer 55 consisting of two parallel sprocket chains

19 running over sprockets 20 and 21 secured to shafts 22 and 23 as shown. Shaft 23 is extended at one end and carries a gear 24 meshing with a gear 25 on a shaft 26, said gear 25 in turn meshing with a pinion 27 on the motor shaft 28 of an ordinary electric motor 29. The chains 19 are provided at suitable intervals with elevating hooks 30 arranged in pairs as shown, and adapted 60 to engage and support trunnions 31 projecting laterally from each side of the upper portions of the different sign members 32, which as shown, are letters of the alphabet.

The case 17 is provided at the rear with 70 a movable door 33 giving access to the interior thereof and a removable hopper or carrier 34 is arranged to be inserted or removed through said door, and said door thus serving as manually operable means for 75 locking said carrier in the case. The hopper 34 is open at the rear and is provided at its forward end with laterally extending vertical guide channels 35 extending from the top to the bottom thereof. At the bottom the 80 hopper 34 is provided at each side with a supporting block 36 having a positioning rib 36' on the bottom thereof adapted to fit within a groove in a supporting block 37 secured to the corresponding side of the 85 case 17. A guide apron 38 and guide flanges 39 are arranged at the upper end of the elevator in case 17 to engage the sign members 32 and their laterally extending trunnions 31 to disengage said sign members 90 from the hooks 30 and discharge them into the top of hopper 34 with their trunnions traveling in the guide channels 35. As indicated, the guide channels 35 are given a slightly forward inclination which causes 95 the sign members 32 to turn over in hopper 34 as they travel downwardly and thus assume their original positions therein. The hopper 34 is provided with a downwardly 100 swinging bottom 40 carrying slide bolts 41 adapted to engage corresponding openings or sockets 41' provided in the side walls of hopper 34, said bottom 40 thus permitting of the ready transportation of the sign members in the hopper 34 and the ready discharge 105 thereof when desired.

Spring held supporting fingers 42 are arranged immediately under the lower ends of the channels 35 being normally held in elevated positions by means of leaf springs 110 43 and in position to temporarily support the trunnions of the lowermost sign member

- in hopper 34. Transfer disks 44 are positioned as indicated on shaft 26 and provided with notches 45 adapted to engage the trunnions 31 of a sign member supported by said fingers and withdraw said sign member from said hopper and from the support of fingers 42, said notches serving to transfer said trunnions on to guides 46 on the side walls of the case 17 where said trunnions are engaged by the hooks 30 and carried upwardly by the elevating chains 19 to be discharged into the top of hopper 34 in the order in which they are removed from the bottom thereof.
- 15 By this arrangement, it will be observed that if the sign members 32 are arranged in hopper 34 in proper order to spell the various words of a sign, they will be automatically removed from said hopper, displayed in proper order through the glass 18 and returned to the top of said hopper, such arrangement permitting of the use of a large number of sign members in compact space and also permitting of the ready removal of one hopperful of sign members and the substitution of another hopperful of differently arranged sign members, thus facilitating the ready changing or altering of the sign exhibit.
- 20 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.
- 25 Having described my invention what I claim as new and desire to secure by Letters Patent is:
1. A sign comprising a case; a carrier removably mounted in said case and adapted and arranged to contain a complete set of sign members; manually operable members for locking said carrier in said case; a traveling conveyer arranged to exhibit said sign members; means for withdrawing sign members from said carrier, and operatively connecting them with said conveyer; and means for withdrawing said sign members from said conveyer and discharging them into said carrier, substantially as described.
- 40 2. A sign comprising a case; a carrier removably mounted in said case and adapted and arranged to contain a complete set of sign members; manually operable means for locking said carrier in said case; a traveling conveyer arranged to exhibit said sign members; means for withdrawing sign members from said conveyer and discharging them into said carrier, substantially as described.
- 45 3. A sign comprising a case; a carrier removably mounted in said case and adapted and arranged to contain a complete set of sign members; and means for removing sign members from said carrier, exhibiting them and then returning them to said carrier, substantially as described.
- 50 4. A sign comprising a case; a hopper in said case adapted and arranged to receive sign members at the top and discharge them at the bottom; a plurality of sign members, each having laterally extending trunnions; a conveyer in operative relation with said hopper; toothed disks operating under said hopper and arranged to engage the trunnions of the bottom-most sign member therein and remove said sign member therefrom; means for effecting engagement between said removed sign member and said conveyer; and means for disengaging said sign member from said conveyer and redepositing it in said hopper, substantially as described.
- 55 5. A sign comprising a case; a removable hopper adapted to contain sign members, said hopper being provided with guide channels extending from the top to the bottom thereof; a removable bottom for said hopper; sign members having laterally extending trunnions arranged to travel in said guide channels; an elevator consisting of two parallel chains having hooks adapted to engage said trunnions; guide members at the top of said elevator adapted to engage said sign members and trunnions, release them from said hooks and discharge them into the top of said hopper; spring held fingers arranged to support the trunnions of the bottommost sign member in said hopper; toothed disks operating under said hopper and arranged to engage the trunnions of the bottommost sign member therein and remove said sign member therefrom; and guides adapted to engage the trunnions of the sign members removed by said disks and direct the same into engagement with the hooks on said chains, substantially as described.
- 60 6. A sign comprising a casing; a hopper in said casing, provided with guide channels extending from the top to the bottom thereof; sign members having laterally extending trunnions arranged to travel in said guide channels; an elevator consisting of two parallel chains having hooks adapted to engage said trunnions; guide members at the top of said elevator adapted to engage said sign members and trunnions, release them from said hooks and discharge them into the top of said hopper; spring held fingers arranged to support the trunnions of the bottommost sign member in said hopper; toothed disks operating under said hopper and arranged to engage the trunnions of the bottommost sign member therein and remove said sign member therefrom; and guides adapted to engage the trunnions of the sign members removed by said disks and direct the same into engagement with the hooks on said chains, substantially as described.

and arranged to engage the trunnions of the bottommost sign member therein and remove said sign member therefrom; and guides adapted to engage the trunnions of 5 the sign members removed by said disks and direct the same into engagement with the hooks on said chains, substantially as described.

In testimony whereof I have signed my name to this specification in the presence of 10 two subscribing witnesses.

ARCHIBALD D. MCKELLAR.
